UNITED STATES PATENT OFFICE

LESLIE B. CLIFFORD, OF TEXARKANA, ARKANSAS

AIR OR GAS LIFT FOR FLUIDS

Application filed May 13, 1927. Serial No. 191,113.

This invention relates to improvements in air or gas lifts for fluid pumps.

The primary object of the invention is to provide an air gas lift that may be produced at commercially practical costs and which will operate with a high degree of efficiency.

More specifically the present invention seeks to provide an air or gas lift for fluids wherein there will be a complete and uniform 10 aeration of the liquid, thereby increasing the efficiency of the lift.

With these and other objects in view the invention consists in certain novel details of construction and combinations and arrangements of parts, all as will hereinafter be more fully described and the novel features thereof particularly pointed out in the appended claims.

In the accompanying drawings, 20 Figure 1 is a vertical sectional view of the lower portion of a well casing with the present lift installed therein;

Fig. 2 is a top plan view of the air or gas nozzle of the ejector; and

Fig. 3 is a sectional view on the line 3—3 of Fig. 2.

Air lifts are rather extensively used for raising water and oil from deep wells and in the present instance there is illustrated a 30 portion of well casing C which extends upwardly to the surface of the ground. The fluid in well casing C enters the lower end 10^a of an eduction pipe 10 and in accordance with the present invention said pipe is formed 35 with a restricted portion 11 so that the upper portion 12 of said pipe, which extends to the ground surface, is considerably smaller than the lower or inlet end 10^a. In this way, the lower portion 10^a constitutes an enlarged 40 liquid chamber.

Extending down the exterior of the eduction pipe but within the casing is a suitable air or gas line 13 connected at its lower end to a fitting 14 in the eduction pipe at a point 45 below the tapered portion 11. On the interior of pipe 10, fitting 14 is connected by pipe 16 to an air or gas nozzle 15. Nozzle 15 has an enlarged air chamber 17 therein from 50 which air or gas is discharged through ducts 18 to the interior of the eduction pipe.

To secure a complete and uniform aeration of liquid passing nozzle 15, the liquid is caused to flow in film like formation as it passes the discharge ducts 18 and the latter are so arranged that the air issues therefrom in a 55 path at an angle to said fluid film whereby the air will effectively penetrate said film and become thoroughly commingled with the liquid.

Various means might be employed to effect a sheeting or filming of the liquid but this is preferably accomplished by tapering the casing to form the restricted portion 11 before mentioned and by having the nozzle 15 so located with respect to said tapered portion that a narrow throat 19 is formed 60 through which liquid rising to the ground surface must pass. Preferably the upper end of nozzle 15 is in substantial transverse alignment with the smaller or upper extremity of 65 tapered section 11 and the discharge ducts 18 of said nozzle discharge the air or gas at this point where the liquid passes this most restricted portion of throat 19.

The preferred formation of ducts 18 consists in providing a circular baffle 20 at the upper end of nozzle 15 which is cylindrical, said baffle being spaced from the wall of the nozzle by small lugs or webs 21. With this construction, a substantially continuous, unbroken circular air or gas spray is emitted 70 from the nozzle and by having the end of the nozzle and the periphery of the baffle beveled, as at 22, the air or gas will be discharged 75 at an angle to the plane of the film or sheet 80 of fluid moving along the tapered surface 11 of the eduction pipe. Such an arrangement 85 will be found exceedingly efficient in operation, giving a large and continuous flow of fluid with the use of a minimum quantity of 90 air. This is believed to be due to the complete and uniform aeration of the fluid which 95 is obtained by having the tapered portion of the eduction pipe direct the sheet or film of fluid toward the nozzle while the discharge ducts of the latter are so constructed as to direct the air or gas at an angle to said sheet or film of fluid at a point where said sheet or film is of minimum thickness.

It will be understood that the upper end 100

of supply pipe 13 communicates with suitable means for supplying nozzle 15 with the aerating medium under proper pressure. If desired, said supply pipe 13 can be attached 5 in any suitable way to the eduction pipe in order to aid in supporting it in the well. While the construction illustrated is the preferred embodiment of the invention, it will be appreciated that various details of the 10 present arrangement may be altered without departing from the spirit of the invention so that such details are to be considered as limitations only as expressly defined in the following claims.

15 What I claim is:

1. In an air or gas lift for fluids, the combination of an eduction pipe tapered intermediate its ends to form an enlarged inlet end and an outlet end of reduced cross section, and an air or gas nozzle within said pipe, said nozzle having discharge ducts positioned in substantial transverse alignment with the smaller end of the tapered portion of said pipe, said discharge ducts being disposed radially outward at an angle to the wall of said tapered portion.

2. In an air or gas lift for fluids, the combination of an eduction pipe tapered intermediate its ends to form an enlarged inlet end and an outlet end of reduced cross section, a tubular nozzle within said pipe having its discharge end positioned in transverse alignment with the reduced end of the tapered portion of said pipe, and a baffle in the discharge end of said nozzle whereby currents of air or gas issuing from said nozzle are directed transversely of the pipe and a thorough commingling of the fluids and air or gas obtained.
